UNITED STATES PATENT OFFICE.

GEORGE LEWIS PATTERSON, OF NEW YORK, N. Y., ASSIGNOR TO ALICE C. PATTERSON, OF NEW YORK, N. Y.

ELECTRIC BELL.

No. 910,412.

Specification of Letters Patent.

Patented Jan. 19, 1909.

Application filed October 17, 1907. Serial No. 397,864.

To all whom it may concern:

Be it known that I, GEORGE L. PATTERSON, a citizen of the United States, residing at New York, county of New York, State of New York, have invented certain new and useful Improvements in Electric Bells, of which the following is a full, clear, and exact description.

My invention relates to an improvement in electric bells and the like, the object being to provide a superior construction whereby electric bells may be quickly and easily installed and whereby, when installed, the operating mechanism including the circuits, terminals, magnets, etc., will be protected from external dust and dampness. The construction is also such that the electric bell mounting or receptacle may be installed, for example, when a house is built, so that the bell proper and operating mechanism may be quickly installed therein at a later time.

Figure 1 is a plan view of a bell and certain of the associated parts; Fig. 2 is a side elevation, partly in section; Fig. 3 is a sectional view, partly broken away; Fig. 4 is a front elevation of the receptacle.

1 represents the receptacle which is hollowed out to receive the socket 2, which in this particular instance includes two terminals 3 and 4 (Fig. 4).

5 is a conduit through which the wires of the circuit pass (see Figs. 2 and 3). In ordinary building construction it is customary to provide conduits for the safe-guarding and protection of circuit wires. In this instance the part 5 represents one end of such a conduit, and this leads into and makes connection with the receptacle 1. This receptacle 1, in ordinary building construction, would be placed substantially flush with the wall in which the bell is to be located.

The apparatus is provided with the usual gong 6, mounted on the extension 7 of the frame support 8; also the usual hammer 9 operated by electro magnets 10 in the ordinary manner. This frame 8, as shown, is substantially flat and carries the binding posts 11 and 12.

13—14 are the wires which respectively lead from the binding posts 11 and 12 to a plug 15, having two terminals adapted to be inserted in the socket 2. Within the receptacle 1 is sufficient space to receive the slack of wires 13—14, when the parts are assembled.

16 is a cover for the electro magnets and associated parts, which is secured to the frame 8.

17—18 are bosses within the receptacle 1, by means of which the frame 8 may be secured thereto by the usual screws, as indicated at 19—19 (Fig. 1).

When the frame 8 is secured to the receptacle 1, there remains nothing to do but to attach the cover 16. This may be easily effected by means of screws passed through the screw-passages 20 (Fig. 1) in the frame 8.

From the foregoing it will be seen that the receptacle 1 is of a suitable construction to provide a well protected, solid foundation. 70 The plug 15 is connected with socket 2. The bell frame 8 is then secured to receptacle 1 by the aforesaid screws and, if desired, by means of an additional screw 21. Finally the cover 16 is applied. Between the cover 75 16 and the frame 8, and between the frame 8 and the receptacle 1, packing gaskets are introduced.

The proper position of the bell is indicated in the several figures and, as will be seen 80 when the parts are assembled, it is practically impossible for dust or water to enter the receptacle or cover from the outside. In the event condensation should take place in conduit 5, any slight amount of dampness that 85 might enter from this source could readily escape through the outlets 22.

It is unnecessary to describe the particular construction of the circuits, or the mechanism by which the hammer is connected, 90 since that may be modified in various ways.

As will be observed, the connections for the binding posts 11 and 12 are made at the back, instead of at the edge of the frame 8, as will be seen in Fig. 3. Thus, by this construction, not only is the bell-operating mechanism thoroughly protected, but the terminals are likewise safe-guarded.

What I claim is,

1. In a device of the character described, a 100 hollow receptacle open at its front side only, terminal connections therein and carried thereby, a plate adapted to close the open side of said receptacle, and means for securing said parts together, terminal connections 105 at the rear of said plate and adapted to be connected to the first-mentioned connections, translating mechanism carried by said plate externally thereof, a protecting cover secured to said plate on the side opposite to 110

said receptacle said plate serving both as a frame support for said translating device and also as a closure for said receptacle.

2. In a device of the character described, a plate, electro-magnetic bell-operating mechanism carried thereby, terminals passing through said plate, a protecting cover for said terminals detachably secured to one side of said plate, a hollow receptacle detachably secured to the other side of said plate and

open at one side, terminal connections leading into said receptacle and adapted to be connected with the aforesaid terminals passing through said plate, said plate also operating to close the open side of said receptacle. 15

GEORGE LEWIS PATTERSON.
